United States Patent

Des. 234,418

Patented Mar. 4, 1975

234,418

PASSENGER VEHICLE BODY

Thomas Forsey, Jr., Akron, and David D. Tompkins,
Columbus, Ohio, assignors to The Goodyear Tire &
Rubber Company, Akron, Ohio

Filed May 25, 1972, Ser. No. 257,062
(Filed under Rule 47(a) and 35 U.S.C. 116)

Term of patent 14 years

Int. Cl. D12—03

U.S. Cl. D12—40

FIG. 1

FIG. 2

FIG. 3

FIG. 4

FIG. 5

FIG. 6

FIG. 7

FIG. 1 is a side elevational view of a passenger vehicle body showing our new design;

FIG. 2 is a perspective view thereof showing one end and the side opposite that shown in FIG. 1, with the doors being open to show the opposite end which is substantially plain and unornamented;

FIG. 3 is an end elevational view thereof;

FIG. 4 is a perspective view of a passenger vehicle body showing a second embodiment of my new design;

FIG. 5 is a perspective view thereof showing the side and end opposite that shown in FIG. 4;

FIG. 6 is a perspective view thereof taken from a different angle than that shown in FIGS. 4 and 5; and

FIG. 7 is a perspective view thereof taken from still another angle other than that shown in FIGS. 4, 5 and 6.

The undisclosed top is substantially flat and unornamented.

We claim:

The ornamental design for a passenger vehicle body, substantially as shown and described.
